CLAIM

The ornamental design for a wheel for automobile as shown and described.

DESCRIPTION

FIG. 1 is a front and left perspective view of a wheel for automobile, showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The claimed design is indicated by the relatively dark portions, while the relatively light and blurred portions form no part of the claimed design.
